George W. Ring, Assignor to
Johnson, Cox & Fuller of Troy, N. Y.
Letters Patent, No. 310. Dated August 27, 1850.

The Schedule referred to in these Letters Patent and making part of the same.

Do all to whom these presents shall come:

Be it known that I, George

Wes. 310

31

W. Ring, of Troy, in the County of Rensselaer, and State of New York, have invented or produced a new design of Parlor Stove plates, and I do hereby declare that the following is a full and exact description of the same, reference being had to the annexed drawings, which make a part of this specification; in which fig. 1. is a view of a front plate of a stove, and fig. 2. an end view of the same.

The design of my stove consists in style of gothic architecture.

What I claim as new and desire to secure by Letters Patent is the design and configuration of ornamental stove plates, substantially the same as described and represented in the annexed drawings.

Witnesses.
